INVENTOR.

UNITED STATES PATENT OFFICE.

WILLIAM HENRY MARSHALL, OF CHELSEA, MASSACHUSETTS, ASSIGNOR TO
HERBERT E. STREETER.

GAME.

SPECIFICATION forming part of Letters Patent No. 429,312, dated June 3, 1890.

Application filed August 15, 1889. Serial No. 320,816. (No model.)

To all whom it may concern:

Be it known that I, WILLIAM HENRY MARSHALL, a citizen of the United States, and a resident of Chelsea, in the county of Suffolk 5 and State of Massachusetts, have invented a new and useful Improvement in Game-Boards or Puzzles, of which the following is a full, clear, and exact description, reference being had to the accompanying drawings, forming 10 a part of this specification in explaining its nature.

The invention relates to a game-board or puzzle, comprising a box or other equivalent or suitable device having a space inclosed by 15 a wall, and having at one or more points an opening through said wall into an inclosed chamber or space, and a ball, preferably of light material—such as pith or cork, paper-pulp, or thin glass—contained within said 20 wall and adapted to be forced by the breath through the hole thereof into the inclosed chamber, the game being to blow the ball through the hole in the wall. This cannot be easily accomplished because the air in the 25 confined space beyond the wall acts as an air-cushion or to return or prevent the ball from entering the hole except under very favorable circumstances.

Of course the invention may be put into a 30 great many different forms, and in the drawings I have shown but one of them.

Referring to the drawings, Figure 1 is a view in perspective of the box or apparatus with which the game is played. Fig. 2 is a 35 view of the box with the upper plate forming the top of the inclosed chamber removed. Fig. 3 is a view of said plate. Fig. 4 is a view of the box and its cover reduced in size, the corner of the cover of the box being re- 40 moved.

A is the box. a is the bottom of the box; a', the wall thereof; a², the inclosed chamber or space.

B is the ball.

45 The inclosed chamber or space is represented as formed by the triangular pieces C C', preferably of wood, having their bases extending against the opposite walls of the box, and being of a length, when so fastened

in place, to provide a small opening or hole 50 D. The space and the pieces C C' are covered by the pasteboard strip E. This provides a cheap construction, and one which allows the ball, after it has been blown into the inclosed chamber, by tipping the box to 55 be easily guided to the entrance or hole through which it escapes. I prefer on some accounts that the front edges of the pieces C C' be curved, as represented, as by so doing the ball is directed toward the opening or 60 hole, and it is apparently more easy to blow the ball through the hole; but this is delusive, as such is not the case. The box has a cover F.

In use the ball is placed anywhere in the 65 open inclosed space, and is then blown by the breath toward the recess or hole, the object of the effort being to cause the ball to be blown through the recess or hole into the chamber beyond. This, however, cannot readily be done, because of the resistance of the air in said chamber, especially while the breathing or blowing of air against the ball continues, the resistance and return-current of the air serving to prevent the ball from 75 readily entering the chamber through said hole, although the ball may be at the very entrance to the chamber.

It is obvious that the invention may be represented in many different forms, and that 80 the box may be of pasteboard, wood, metal, or any other suitable material.

It is of course apparent that the wall about the board or base a may be dispensed with without departing from the spirit of the in- 85 vention.

Having thus fully described my invention, I claim and desire to secure by Letters Patent of the United States—

1. The improved game-board or puzzle, comprising an inclosed chamber mounted upon the board or support, and having a suitable entrance and otherwise substantially airtight, the said board or support extending in front of said entrance and forming a table 90 or support for a light ball, and the said ball by which the game is played by being moved or blown toward and through said opening

into said inclosed chamber, substantially as described.

2. In a game-board or puzzle of the character specified, the inclosed chamber a^2 , having the hole or entrance D thereto, otherwise practically air-tight, with the inclined or curved outer wall on each side of said en-

trance, and a ball capable of being blown into said chamber through said entrance, substantially as described.

WILLIAM HENRY MARSHALL.

In presence of—

F. F. RAYMOND, 2d,
J. T. BALL.
